(57) **CLAIM**

The ornamental design for a squeegee tool having a fixed blade, as shown and described.

DESCRIPTION

A portion of the disclosure of this patent document contains material which is subject to copyright protection. This patent document may show and/or describe matter which is or may become trade dress of Unger Marketing International, LLC. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a perspective view of a squeegee tool having a fixed blade, showing our new design;

FIG. 2 is a top plan view of our design shown in FIG. 1;

FIG. 3 is a bottom view of our design shown in FIG. 1;

FIG. 4 is a side view of our design shown in FIG. 1;

FIG. 5 is another side view of our design shown in FIG. 1; FIG. 6 is front view of our design shown in FIG. 1; and, FIG. 7 is a back view of our design shown in FIG. 1.

The broken lines depict portion of the squeegee tool having a fixed blade that form no part of the claimed design.

References to "side," "top," "bottom," "front," and "back" in the Figure Descriptions are not necessarily meant to require any specific orientation of the article as viewed. A squeegee according to the claimed design may be used in any orientation.
